UNITED STATES PATENT OFFICE.

EARL L. BROWNSON, OF ALLSTON, MASSACHUSETTS, ASSIGNOR TO NATIONAL BINDING MACHINE COMPANY, OF BOSTON, MASSACHUSETTS, A CORPORATION OF MAINE.

STRIP-SERVING APPARATUS.

1,202,664.

Specification of Letters Patent.

Patented Oct. 24, 1916.

Application filed April 25, 1907. Serial No. 370,195.

To all whom it may concern:

Be it known that I, EARL L. BROWNSON, a citizen of the United States, residing at Allston, in the county of Suffolk and State of Massachusetts, have invented an Improvement in Strip-Serving Apparatus, of which the following description, in connection with the accompanying drawings, is a specification, like letters on the drawings representing like parts.

This invention relates to devices or apparatus for supplying strips of paper or the like that may be employed for wrapping or binding packages or to serve as labels to be applied to bottles or other receptacles, and has particular reference to that type of apparatus employing a support for a coil of the paper strip which has been previously gummed on one side and then dried, and having means for moistening the gummed side of the strip as the latter is drawn from the coil. An ungummed strip of paper or the like may be employed, in which case the moistening device is suitably positioned and constructed to apply an adhesive instead of water to the strip.

In order that the principles of my invention may be clearly understood, I have disclosed one type or embodiment thereof in the accompanying drawings, wherein—

Figure 1 is a view partly in side elevation and partly in vertical section of a form of apparatus embodying my invention; Fig. 2 is a plan view of the apparatus shown in Fig. 1, the cover being removed to disclose the construction of parts. Fig. 3 is a perspective view representing a preferred form of casing to receive the operating parts of the mechanism, certain of which are removed therefrom; and Fig. 4 is a vertical, transverse section of said casing and the mechanism supported therein.

Referring more particularly to that single type or embodiment of my invention herein selected for illustration, the casing wherein the apparatus preferably is mounted is indicated at 1, it being of any suitable material and shape or size and adapted to contain therein in any suitable and preferably readily removable manner one or a plurality of coil strips 2 of paper or the like, three such strips being herein indicated in Fig. 2 and constituting strip packages. Preferably the strips are supported upon a single spindle 3, and any suitable tensioning means

may be employed, whereby the strip is suitably tensioned as it is delivered for severing or use.

While strip feeding, strip moistening and strip severing devices of any suitable type may be employed, herein I contemplate the use of automatic strip feeding means, movable strip moistening means and stationary strip severing means. The strip feeding means and strip moistening means may be operated in any desired sequence, but herein I preferably operate first the strip moistening means to moisten an exposed portion or length of strip and then operate and preferably but not necessarily automatically the strip feeding means, whereby the moistened strip is automatically fed into a position whereby it may be severed. As stated, any suitable type of severing means may be employed to be operated automatically or otherwise. Preferably I employ a common means to operate the moistening and the feeding devices, and herein for the purpose provide a lever having a plurality of arms 4 as indicated in Fig. 2 pivoted in the rear of the moistening strip or strips at 5 and adapted to be depressed between or at the sides of said strip or strips. In the forward portion of the casing 1, which is of preferably reduced height, I dispose a reservoir 6 having a suitably mounted therein for vertically sliding movement a preferably hollow metallic case 7, herein shown as slotted at 8 to receive for guiding movement the pin 9. A moistening strip 10 is positioned upon the case 7 so that preferably both ends thereof may be received in the water in the reservoir 6. The reservoir 6 is provided with a knob 6' by which the same may be withdrawn when desired from the casing in which the same is removably positioned. The pin 9 is horizontally disposed in the casing 1, positioned for vertical movement in suitable slots therein. Suitably secured thereto as at opposite ends thereof are vertically disposed strips, one of which is indicated in dotted lines in Fig. 1 and to which are suitably connected as by vertically disposed rods 12 a connecting yoke or member 13 between which and the top of the casing is disposed a coil spring 14 whereby the yoke 13 is normally held elevated. The said yoke 13 preferably extends entirely across the moistener as indicated in Fig. 2. Suitably connected to the pin 9 and preferably at opposite ends thereof are pairs

of links 15 pivotally connected to levers 16 pivoted in the side walls of the casing as represented at 17, so that their free end 18 may engage the lower surface of the case 7, whereby when the yoke 13 and pin 9 are depressed the free ends of said levers are elevated, thereby to raise the moistener into strip moistening relation. In the operation of the parts the lever 4 when depressed engages the yoke 13, thereby compressing the spring 14 and operating the levers 16 to elevate the moistener, which, when the handle 4 is elevated, is by the spring 14 or the weight of the parts returned to non-strip moistening relation. It is apparent that any suitable strip moistening mechanism may be employed, though herein I contemplate a moistener that is relatively movable with respect to the strip.

20 In order suitably to feed the strip any suitable mechanism may be employed. Herein for the purpose I provide a rack 19 pivoted to and depending from the lever 4, a plurality of such racks preferably being employed if more than one strip be used. Suitably disposed with respect to the coil 2 is a lower feeding roll 20 and an upper feeding roll 21 between which the end of the strip is delivered. The lower roll 20 is loosely mounted upon a spindle 22 having fast thereon a pinion 23 and a ratchet 24 with which engages a pawl 25 pivoted upon the roll 20 and preferably suitably spring pressed. The rack 19 being in meshing engagement with the pinion 23, when the lever 4 is depressed into engagement with the yoke 13 to elevate the moistener, no movement of rotation is imparted to the roll 20, but upon the upward movement of the lever 4 the rack 19 imparts a forward or feeding movement of rotation to the roll 20 and hence to the roll 21. Thus, in the present embodiment of my invention, when the lever 4 is depressed, the moistener is operated or lifted into moistening relation and following such movement the feeding rolls are operated in the manner described. I preferably employ any suitable means whereby a predetermined length of strip may be fed, and herein and in order that such length of strip may be varied, I provide in the casing a series of openings 26, within which I may place a peg or stop to limit the upward or feeding movement of the lever 4. Any other suitable means may be employed for the purpose. I may employ any suitable means automatically to operate the feeding mechanism, but herein for the purpose I provide a coil spring 27 attached to the lever 4 and in any suitable manner to the interior of the casing, as indicated, whereby the lever is automatically returned or elevated after the moistening action.

65 It is frequently desirable to provide means to hold the rack or racks 19 in such relation

to the pinion or pinions 23 that they may be disengaged therefrom. For the purpose I provide a series of rock shafts 28, 29 and 30 mounted in the casing and each having exteriorly exposed operating handles 31, 32 and 33. Suitably mounted upon said rock shafts so as to engage the respective racks are arms 34 carrying rolls 35. When the handles 31, 32 and 33 are moved to the right viewing Fig. 1, the respective rolls 35 are moved from engagement with the racks, and the springs 36 secured to the lever 4 swing said racks into inoperative position. It will be apparent that by the construction herein shown, the feeding devices for one or more of the coils may be thrown into inoperative position while leaving others in operative position. If it be desired to serve one or more of the strips by draft thereon by the operator, one or more of the handles 31, 32 and 33 may be moved to the right viewing Fig. 1, thus rendering inoperative the mechanical strip feeding devices relating thereto. The yoke 13 may be depressed by hand, thus sufficiently elevating the moistener, and the end of the strip being drawn upon the desired length may be drawn across the moistener and thereafter severed.

Any suitable guiding means may be employed to support and guide the strip to be moistened and to guard against undue moistening of the strip or strips. Herein for the purpose, I have provided a plurality of horizontally disposed guiding edges 37 preferably fixedly mounted in the casing and receiving upon their upper spaced edges the strip or strips. Any suitable number of such guide edges may be employed and if desired a plurality may be used for each strip. Preferably the case 7 and moistener 10 are slotted through a portion of their extent to permit the vertical movement of said parts with relation to said edges.

If it be desired to moisten a shorter portion of the strip than the length of the moistening surface, removable plates of variable length may be employed to be positioned between the strip and the moistener at that portion of the moistener adjacent the feeding rolls 20 and 21 and projecting 115 to the desired extent toward the front of the casing, whereby any desired portion of the moistener may be exposed. Any other suitable means may be employed to vary the exposed extent of the moistener.

Any suitable strip severing mechanism may be employed. Herein I employ a stationary cutting device 38 mounted upon the casing 1 as at the forward end thereof, whereby after the strip has been moistened 125 and the proper length has been fed forward it may by hand manipulation be severed.

The rolls 20 and 21 not only constitute feeding rolls, but they serve as holding means whereby the unsevered, free end of 130

the strip is held in exposed position beyond the moistener, where it can be grasped by the hand of the user when it is desired to use a portion of the strip, which is thereupon manually severed against a suitable cutting device, hereinafter set forth.

It is apparent that within the scope of my invention, I may employ a separate moistener for each strip and that whether one or 10 more moisteners be employed I may employ a separate actuating means as a lever for feeding each strip. In such event, I may employ separate and adjustable means, whereby a predetermined length of strip is 15 fed from each coil. In this manner the means for determining the length of strip fed from each coil may be so positioned as that different length strips may be fed simultaneously or substantially simultaneously 20 from the coils. This may readily be done if two coils are employed by mounting adjustable stops in opposite side walls of the casing to limit the separate levers respectively operating the feeding means for said strips. 25 Any other suitable means accomplishing this end may, if desired, be employed.

In Figs. 3 and 4 I have represented a preferred form of casing wherein the operating parts of the mechanism are mounted. In 30 said figures the base 39 has preferably integrally formed therewith the side 40 and end 41. A portion of the opposite side 42 is movably connected with the base along a longitudinal line of the latter and preferably 35 by means permitting the outward swinging and bodily removal of said side, said means herein comprising curved lugs 43 received in sockets 44 of the base 39. The cover portion 45 is preferably integrally 40 formed with the side 42 and carries suitable fastening means, as set screws 46, adapted to enter openings 47 in the upper edge of the side 40. Preferably, a cover 48 is hinged or 45 otherwise secured and preferably in a manner to permit separation from the front wall 49 of the casing which rises in the rear of the moistening mechanism and is provided with slots 50 to permit the operation of the levers 4. The coil of paper or the like 50 may be supported in any suitable manner in the casing, as upon the spindle 51 secured to the inner face of the side 40. Preferably, a frame having side walls 52 and 53, connected in any suitable manner, is mounted in 55 the casing and preferably in a manner permitting removal thereof from the casing. Herein the frame is provided with projecting pins 54, adapted to be received in sockets or openings in the side 40. If desired, the side 42 of the casing may be provided with a recess to receive and support the said frame. The rock shafts 28, 29 and 30 are 60 suitably mounted in the side 40 of the casing and are removably connected as by a polygonally shaped socket and correspond-

ingly shaped shaft to the handles 31, 32 and 33, thus permitting the ready removal of the frame.

Having thus described one type or embodiment of my invention, I desire it to be 70 understood that although I have employed specific terms, they are used in a generic and descriptive sense and not for purposes of limitation.

Claims:

1. A strip serving apparatus comprising strip package supporting means, a moistener in wetting relation to the strip issuing from said supporting means and positioned to permit the delivery of the unsevered, forward end of the strip past it to the hand of the user, and predetermined-length feeding means manually operable by the user to effect the feeding of a predetermined length of said unsevered, forward end to and past 85 the moistener to the user.

2. A strip serving apparatus comprising strip package supporting means, a moistener in wetting relation to the strip issuing from said supporting means and positioned to 20 permit the delivery of the unsevered, forward end of the strip past it to the hand of the user, and moisture-applying and predetermined-length feeding means wholly in the rear of the moistener and operable by 95 the user to feed a predetermined length of said unsevered forward end of the strip to and past the moistener thereby to effect moistening contact of the strip and moistener and to present a predetermined, unapplied length of strip from the moistener to 100 the user.

3. A strip serving apparatus comprising in combination strip package supporting means, a moistener in wetting relation to 105 the strip issuing from said supporting means and positioned to permit the immediate delivery of the unsevered, forward end of the strip past it to the hand of the user, and automatically acting predetermined-length 110 feeding means positioned in the rear of the moistener to feed a predetermined length of said unsevered, forward end of the strip to and past the moistener and to present the same to the user for manual application.

4. A strip serving apparatus comprising strip package supporting means, a moistener in wetting relation to the strip issuing from said supporting means and positioned to permit the immediate delivery of the unsevered, forward end of the strip past it to the hand of the user, automatically-acting, predetermined-length feeding and holding means to feed an unsevered end of the strip of predetermined length to and past the 120 moistener and positioned to hold and present the same unapplied to the user, and severing means against which the fed predetermined length of strip may be manually 125 severed.

5. A strip serving apparatus comprising strip package supporting means, a moistener in wetting relation to the strip issuing from said strip supporting means and positioned 5 to permit the immediate delivery of the unsevered, forward end of the strip past it to the hand of the user, predetermined-length feeding and holding means manually operable by the user and positioned to effect the 10 feeding to and past the moistener to the user and the holding in position for manual grasping and severance of an unsevered unapplied strip of predetermined length, and strip severing means against which the predetermined, fed length of strip may be 15 manually deflected for severance.

6. A strip serving apparatus comprising strip package supporting means, a moistener in wetting relation to the strip issuing from 20 said strip supporting means and positioned to permit the immediate delivery of the strip past it to the hand of the user, said moistener normally occupying an inactive relation to the strip, manually operable strip 25 feeding means to feed the strip to and past the moistener, and means coöperating with said feeding means, to move said moistening means from inactive to active relation to the strip.

7. A strip serving apparatus comprising strip package supporting means, a moistener in wetting relation to the strip issuing from 30 said strip supporting means and positioned to permit the immediate delivery of the strip past it to the hand of the user, and means operative upon movement in one direction to effect the moistening of the strip and operative upon movement in the opposite direction to feed a moistened strip.

8. A strip serving apparatus comprising strip package supporting means, a moistener in wetting relation to the strip issuing from 40 said strip supporting means, and operating means having oppositely acting moistening effecting movement and feeding movements.

9. A strip serving apparatus comprising strip package supporting means, a moistener in wetting relation to the strip issuing from 50 said strip supporting means and positioned to permit the immediate delivery of the unsevered, forward end of the strip past it to the hand of the user, predetermined-length feeding and holding means manually 55 operable by the user and positioned to effect the feeding of an unsevered, unapplied strip of predetermined length past the moistener and the holding of the unsevered end of said strip in position for manual grasping, 60 a severing blade in advance of the moistener, and operating mechanism to operate said feeding means and to effect the moistening of the strip.

10. A strip serving apparatus comprising 65 strip package supporting means, a moistener

in wetting relation to the strip issuing from said strip supporting means and positioned to permit the immediate delivery of the unsevered, forward end of the strip past it to the hand of the user, means relatively to 70 move the strip and the moistener into contact with each other, and predetermined-length feeding and holding means manually operable by the user and positioned to feed an unsevered predetermined length of strip 75 to and past the moistener and to hold such unapplied length of strip in exposed position to be grasped by the hand of the user.

11. A strip serving apparatus comprising strip package supporting means, a moistener in wetting relation to the strip issuing from 80 said strip supporting means and positioned to permit the immediate delivery of the unsevered, forward end of the strip past it to the hand of the user, said moistener being normally supported out of wetting relation to the strip issuing from said supporting means, moistener operating means to move the moistener into strip moistening relation and manually operative strip feeding and 85 holding means to feed the strip for moistening and positioned to hold the unsevered end of the strip in exposed position to be 90 grasped by the hand of the user.

12. A strip serving apparatus comprising 95 means for supporting a plurality of strip packages, a moistener in wetting relation to the strips issuing from said supporting means, feeding means for said strips, and means to disengage one or more of said 100 feeding means.

13. A strip serving apparatus comprising supporting means for a plurality of strip packages, a moistener in wetting relation 105 from the strips issuing from said supporting means, separate feeding means for the said strip, and means permitting the disengagement of one or more of said feeding means.

14. A strip serving apparatus comprising strip package supporting means, a moistener in wetting relation to the strip issuing 110 from said strip supporting means and positioned to permit the immediate delivery of the unsevered, forward end of the strip past it to the hand of the user, automatically acting, predetermined-length feeding and holding means positioned to effect the feeding to and past the moistener of a predetermined length of strip and the holding of the same in exposed position to be 115 grasped by the hand of the user and means to vary such predetermined length.

15. A strip serving apparatus comprising strip package supporting means, a movably mounted moistener in wetting relation to the strip issuing from said supporting means and positioned to permit the delivery of the unsevered, forward end of the strip past it to the hand of the user, strip 125

- feeding and holding rolls positioned to permit the direct feeding to the hand of the user of an unsevered, unapplied length of strip and the holding of the unsevered end 5 of the strip in exposed position to be grasped by the hand of the user, an operating lever, and means for operating said rolls and said moistener through the instrumentality of said lever.
- 10 16. A strip serving apparatus comprising strip package supporting means, a movable moistener in wetting relation to the strip issuing from said supporting means and positioned to permit the delivery 15 of the strip past it to the hand of the user, a feed roll or rolls having a pinion operating lever, a rack carried by said lever to engage said rolls, and means whereby upon movement of the lever the moistener is 20 moved into strip moistening relation.
17. A strip serving apparatus comprising strip package supporting means, a moistener located below the path of travel of the strip and movable to and from the service 25 path thereof, one or more strip guiding edges longitudinally positioned with respect to the strip and in the path of travel thereof, and predetermined-length feeding means manually operable by the user to 30 feed a predetermined length of strip.
18. A strip serving apparatus comprising strip package supporting means, a movable moistener in wetting relation to the strip issuing from said supporting means and positioned to permit the delivery of the strip past it to the hand of the user, strip feeding means, means operative by the strip feeding means to move the moistener into strip moistening relation, and one or more 35 strip guiding edges positioned above the non-moistening position of the moistener.
19. A strip serving apparatus comprising strip package supporting means, a moistener normally in inactive relation to the strip issuing from said strip supporting means, means to render the moistener active, automatically acting, predetermined-length feeding and holding means positioned to effect the feeding of a predetermined length of strip to and past the moistener and the holding of the unsevered end of the strip in exposed position to be 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 896
21. A strip serving apparatus comprising strip package supporting means, a moistener in wetting relation to the strip issuing from said supporting means and positioned to permit delivery of the unsevered, forward end of the strip past it to the hand of the user, a severing blade in advance of the moistener and against which the strip may be manually deflected for severance by the user, and predetermined length feeding and holding means manually operable by the user and positioned to effect a feeding to and past the moistener to the user, of an unapplied strip of predetermined length and the holding of said unsevered, forward end of the strip in exposed position to be grasped by the hand of the user for manual deflection against the severing blade.
22. A strip serving apparatus comprising strip package supporting means, a movably mounted moistener in wetting relation to the strip issuing from said supporting means and positioned to permit the delivery of the unsevered, forward end of the strip past it to the hand of the user, strip feeding and holding rolls positioned to permit the direct feeding to the user of an unapplied length of strip and the holding of said unsevered, forward end of the strip in exposed position to be grasped by the hand of the user, an operating member, and means for operating said feeding and holding rolls and said moistener through the instrumentality of said member.
23. A strip serving apparatus comprising strip package supporting means, a moistener in wetting relation to the strip issuing from said supporting means and positioned to permit the delivery of the unsevered, forward end of the strip past it to the hand of the user, and predetermined-length feeding and holding means manually operable by the user, and means co-acting therewith, together to effect the feeding of a predetermined length of said unsevered, forward end to and past the moistener, and the holding of said unsevered end of the strip, for grasping by the hand of the user.
- In testimony whereof, I have signed my name to this specification, in the presence of two subscribing witnesses.
- EARL L. BROWNSON.
- Witnesses:
- HATTIE L. TOWNSEND,
IRVING U. TOWNSEND.

It is hereby certified that in Letters Patent No. 1,202,664, granted October 24, 1916, upon the application of Earl L. Brownson, of Allston, Massachusetts, for an improvement in "Strip-Serving Apparatus," an error appears in the printed specification requiring correction as follows: Page 5, lines 63-64, claim 20, after the word "moistener" insert the words *and the holding of the unsevered strip in exposed position to be grasped by the hand of the user*; and that the said Letters Patent should be read with this correction therein that the same may conform to the record of the case in the Patent Office.

Signed and sealed this 28th day of November, A. D., 1916.

[SEAL.]

F. W. H. CLAY,

Acting Commissioner of Patents.
